By

UNITED STATES PATENT OFFICE.

WILLIAM PAUL, OF BEECHER, ILLINOIS.

AIR SHOTGUN.

Application filed February 9, 1924. Serial No. 691,618.

To all whom it may concern:

Be it known that I, WILLIAM PAUL, a citizen of the United States, and a resident of the village of Beecher, in the county of

5 Will and State of Illinois, have invented certain new and useful Improvements in an Air Shotgun; and I do hereby declare that the following is a full, clear, and exact description of the same, reference being had 10 to the accompanying drawings and to the numerals of reference marked thereon, which form a part of this specification.

This invention covers improvements in an air shot gun, adapted for firing bullets or 15 other projectiles, by the force of compressed air and furthermore, adapted to fire a plurality of bullets in consecutive order by compressed air from a compressed air chamber, without requiring recharging of the 20 chamber after the firing of each shot.

It is an object of this invention to provide an air shot gun of the breech loading type wherein shot is adapted to be fired from a shell positioned in the inner end of the 25 barrel by means of a predetermined discharge of compressed air from a compression chamber of a capacity sufficient to permit a number of consecutive shots to be fired from a compressed air chamber having an 30 air outlet control valve mechanism operable by a trigger controlled spring actuated operating rod.

It is also an object of the invention to provide an air shot gun wherein the trigger 35 coacts directly with a spring controlled operating rod which when released by the trigger is adapted to operate a spring controlled air release valve governing mechanism which permits of only a predetermined 40 charge of air from a compression chamber.

It is a further object of the invention to provide an air shot gun wherein the trigger co-acting directly with a spring controlled operating rod, is adapted to be set after the 45 firing of each shot, without disturbing the air release control valve mechanism.

It is furthermore an object of this invention to construct an air shot gun wherein the air release valve mechanism is provided 50 with a fulcrumed lever having increased leverage to permit of ready opening of the air outlet valve against the high pressure within an air compression chamber.

Another object of the invention is to provide an air shot gun wherein an air release 55 valve is adapted to close automatically after

a trigger operation so that only a predetermined quantity of compressed air will be discharged from a compressed air chamber each time a shot is fired. 60

It is an important object of the invention to provide an air shot gun of simplified and inexpensive construction wherein the valve controlling the discharge opening of the compressed air chamber is adapted 65 to automatically close after each operation of the trigger without interference by the valve operating mechanism which is spring controlled and slideable in an extension of the gun stock for direct co-action with the 70 notched end of said trigger which serves to hold said valve operating mechanism in release position.

Other and further important objects of this invention will be apparent from the 75 disclosures in the specification and the accompanying drawings.

The invention (in a preferred form) is illustrated in the drawings and hereinafter more fully described. 80

On the drawings:

Figure 1 is a side elevation of an air shot gun embodying the principles of this invention.

Figure 2 is a fragmentary longitudinal 85 section of the gun with parts shown in elevation.

Figure 3 is an enlarged side elevation of the barrel end of the gun showing the operation of the barrel in dotted lines. 90

Figure 4 is an enlarged transverse section taken on line 4-4 of Figure 3.

Figure 5 is an enlarged detailed longitudinal section of the air casing.

Figure 6 is a transverse section taken on 95 line 6-6 of Figure 5.

Figure 7 is a transverse section taken on line 7-7 of Figure 5.

As shown on the drawings:

The reference numeral 1 indicates a gun 100 stock having integrally formed thereon a stock extension or arm 2 connected to said stock by an integral breech section 3. The breech arm 2 is provided with a longitudinal groove or passage 4 the inner end of 105 which communicates with a recess 5 formed within the breech section 3. A second recess 6 is provided in the breech section 3 and communicates with the recess 5. Pivoted in the recess 6 is a trigger 7 one end of which 110 projects from the recess 6 and is protected by means of a trigger guard 8. The inner end

of the trigger 7 has a dog or tooth 9 integrally formed thereon. A coiled spring 10 is seated in the recess 6 and engages against the trigger to hold the trigger cocked and the toothed end 9 thereof in contact with a 5 slideable operating rod 11. The rod 11 is slideable in the groove 4 and projects into the recess 5 and has a tooth 12 formed thereon to co-act with the trigger tooth 9. The 10 rod 11 has formed thereon a finger or projection 13. A head or finger piece 14 is integrally formed on the outer end of the rod 11. Coiled around the rod 11 is a control spring 15 one end of which is secured 15 to the rod while the other end bears against a guide lug 16 through which the rod 11 20 slideably projects.

Resting on the stock extension 2 and secured thereto by means of a screw 17 is a 20 cylindrical casing or compressed air tube 18. The inner end of the casing 18 is closed by a flanged plug 19 held in place by a retaining pin 20. The plug 19 has a claw or tooth 21 formed thereon which projects 25 through an aperture in a metal plate 22 secured against the breech section 3 by screws 23.

Projecting into the casing 18 is an air 30 pump shell or tube 24, the inner end of which seats in a recess in the plug 19. A slot 25 is provided in the inner end portion of the pump tube 24. A valve seat 26 is secured in the air pump tube 24 by a retaining sleeve or collar 27. A passage 28 is provided in the valve seat 26. A valve 29 is normally held against the pump valve seat 26 by means of a coiled spring 30. The spring 30 has one end engaged around a pin on the valve 29 and the other end engaged against a disk 31 secured on one 40 end of a control rod or pin 32 which is slideable through the plug 19. The slideable rod 32 has a second disk or ring member 33 secured thereon within the pump tube 24. A slot 34 is provided in the slideable rod 32 between the disks or rings 31 and 33. A pump piston or plunger 35 is provided in the pump tube 24 and has attached thereto a pump piston rod 36 operable by a handle 37 to cause air to be pumped through the valve passage 28 thereby opening the valve 29 to permit air to be pumped through the slot 25 into the air compression chamber of the casing 18.

Secured on the pump tube 24 are brackets or holders 38 in which a barrel 39 is slideably mounted. A guide rib 40 is formed longitudinally along the under portion of the barrel 39 and stops short of the inner end 55 of the barrel adjacent the outer end of a sleeve 41 fixed within the casing 18. The rib 40 is provided with a notch to receive the free end of a plate spring 42 to hold the barrel in place. The spring 42 is 60 mounted upon the pump tube 24. The outer

end of the barrel 39 is provided with a sight piece 43. The inner end of the barrel 39 is reamed out to afford a bullet recess 44.

A valve seat member 45 is secured within the inner end of the sleeve 41. An air release valve 46 is held against the valve seat 45 to prevent the escape of the compressed air from the casing 18. The valve 46 is secured to a slideable rod or stem 47 against a valve block 48 which is also fixed on said rod. A spring 49 on the valve stem 47 holds the valve 46 in closed position. The spring 49 is positioned between the valve block 48 and a bracket 50 fixed on the plug 19. The stem 47 is slideable through the bracket 50 and slides into a guide recess 51 in the plug 19. A slot 52 is provided in the valve stem 47 adjacent a ring or flange 53. A stud 54 is fixed in the plug 19 and projects into the air chamber of the casing 18. Pivoted to the stud 54 intermediate its ends is a valve control lever 55. The lever 55 is mounted with a longer lower end projecting through the pump tube slot 25 and through the opening 34 in the slideable control rod 32. The upper or shorter end of the lever 55 projects through the opening 52 in the slideable valve stem 47. The lever co-acts with the plates or rings 33 and 53 on the rod 32 and stem 47 respectively, thereby affording substantially a two-to-one leverage so that the air release control valve 46 may be readily opened when the push rod 32 is actuated.

The operation is as follows: 100

Air is pumped into the air casing 18 by operating the air pump piston 35 by means of the pump rod 36. The air pumped by the air pump opens the valve 29 and then enters the compressed air chamber of the casing 18, through the slot 25. Air is pumped until the desired pressure is reached. The spring 49 acts to hold the air release valve 46 in its closed position, thereby preventing escape of the air and also acting to hold the lever 55 positioned as illustrated in Figure 5 with the push rod 32 projected rearwardly through the plug 19 in position to be operated when the trigger is pulled.

The gun is loaded with a shot-loaded bullet by simply pressing down the spring 42 and pulling the rear end of the barrel 39 out of the sleeve 41 into the dotted line position of Figure 3. The bullet is then put into place in the barrel recess 44 and the barrel 39 is pushed back into place. When the barrel 39 is pushed back into position the spring 42 engages in the notch in the guide rib 40 to hold the barrel locked in place. 115

To lock the operating rod 11 in release position it is only necessary to push the rod 11 inwardly against the action of the spring 15 until the toothed end 9 of the trigger registers with the tooth 12 on the rod 11. 139

The spring 10 acts to hold the toothed end 9 of the trigger in contact with the tooth 12 and furthermore is a means for holding the trigger 7 properly cocked ready for operation.

When the trigger 7 is pulled the toothed end 9 thereof is swung out of engagement with the tooth 12 thereby causing release of the operating rod 11. The compressed 10 spring 15 then acts to slide the operating rod 11 outwardly bringing the upturned finger 13 into contact with the end of the valve control rod 32. The rod 32 is thus forced forwardly against the action of the spring 15 and at the same time the disk 33 acts on the lower end of the pivoted lever 55 to swing the same about its pivot so that the upper end of the lever acting against the disk 53 will act to pull the valve stem 20 47 rearwardly thereby opening the release valve 46 against the action of the spring 49. A predetermined quantity of compressed air from the air casing 18 is thus discharged against the bullet in the barrel 39. The load 25 of shot in the bullet is thus fired through the barrel 39 of the gun.

When the trigger 7 is operated, the operating rod 11 rebounds into a position wherein the finger 13 is out of contact with the control rod 32. The spring 49 is thus permitted to act automatically to close the valve 46 almost immediately after the pulling of the trigger. It will thus be noted that only a predetermined quantity of compressed 35 air is discharged from the compressed air chambers each time the trigger is operated. By this arrangement a plurality of shots may be fired without requiring repumping of air into the casing 18 after the firing of each shot.

I am aware that numerous details of construction may be varied through a wide range without departing from the principles of this invention and I therefore do not purpose 45 limiting the patent granted hereon, otherwise than necessitated by the prior art.

I claim as my invention:

1. An air shot gun comprising a stock, an air casing mounted thereon, an air pump 50 connected with the casing for pumping air into the casing, a sleeve fixed in said casing, a control valve closing the inner end of said sleeve, a barrel removably engaged in said sleeve for carrying a bullet to be fired, a slotted valve stem connected with the 55 control valve, a spring engaged around the valve stem for holding the control valve in closed position, a slotted slideable rod projecting through the end of said casing, a lever pivoted in the casing and projecting through the slotted valve stem and through the slotted 60 slideable rod, a spring in said casing between the air pump and said slotted slideable rod, a trigger in said stock, a spring controlled slideable member in the stock for direct co-

action with said trigger, and a projection on said slideable member adapted to actuate the slotted slideable rod when the trigger is pulled to release the slideable member and cause the projection to actuate the pivoted lever to open the control valve.

2. In an air shot gun, the combination with a stock, of an air casing thereon, means for pumping air into said casing, a spring for holding said valve in closed position, a lever pivoted in said casing for actuating said valve, a rod connected with the lever and projecting from the casing, a spring controlled trigger in the stock, and a rod actuating member co-acting directly with the trigger and adapted when the trigger is pulled to operate said rod and lever to cause temporary opening of the valve to permit only a predetermined quantity of air to be discharged from the casing.

3. In an air shot gun, the combination with a stock, of an air pump connected with the casing for pumping air into the casing, a barrel removably projecting into the casing for carrying a bullet, a valve for controlling the discharge of air from the casing into the barrel, a valve stem connected with the valve, a spring for holding the valve in closed position, a rod slideably projecting from the casing, a spring between the pump and said rod, a lever pivoted in said casing and engaged with said rod and with said valve stem, a trigger in said stock, a spring for holding the trigger cocked, and a spring controlled operating mechanism adapted to be held in a release position by said trigger and adapted when the trigger is pulled to actuate the rod, said lever and the valve stem to momentarily open the valve.

4. In an air shot gun, the combination with a stock, a casing mounted thereon, a pump for pumping air into the casing, a sleeve fixed in the casing, a valve controlling the discharge of air from the casing into the sleeve, a barrel projecting into said sleeve adapted to carry a bullet to be fired by compressed air entering said sleeve when the valve is opened, a spring in the casing for holding the valve closed, a slotted valve stem connected with the valve, a disk on said valve stem, a slotted member projecting from the casing, a disk thereon within the casing, a lever mounted in said casing and projecting through the slotted valve stem and through the slotted member and contacting said disks, a spring between the pump and said slotted member to hold the slotted member projected and the pump closed, a spring controlled operating rod slideable in the stock and formed with a finger for actuating the slotted rod, a trigger pivoted in the stock, and a spring for holding the trigger cocked to hold the operating rod in release position.

5. In an air shot gun the combination with

- a stock, of an air casing mounted thereon, a valve for controlling the escape of air from the casing, a lever pivoted in the casing for controlling the operation of said valve, a rod 50
5 slideable in said casing for operating the lever, an operating member for said rod slideably projecting into said stock, a spring for operating the same, a trigger pivoted in the stock, and a spring for holding the trigger
10 cocked and in engagement with said operating member to hold the same in a release position.
6. In an air shot gun the combination with, a stock, of a rod slidably projecting into the stock, a spring in said stock for holding the rod projected from the stock, a compressed air casing on the stock, a valve therein controlling the escape of air therefrom, a valve operating mechanism in the casing having a 60
15 member projecting into the stock in the field of operation of said rod, and a spring controlled trigger in said stock adapted to engage and hold the rod in a release position out of operating engagement with the
20 member forming a part of said valve operating mechanism.
7. In an air shot gun, the combination with a stock and an air casing, of a valve in said casing for controlling the escape of air therefrom, a resilient member for holding the valve closed, a valve operating mechanism in the casing and projecting therefrom, a spring controlled trigger in said stock, an operating member in said stock adapted to be held in release position by said trigger, and means for automatically actuating the operating members when the trigger is pulled to cause the operating member to operate the valve operating mechanism to 70
25 open the valve.
8. In an air shot gun the combination with a compressed air casing, means for pumping air therein, a barrel projecting into the casing, a valve in the casing controlling the entrance of air into the barrel from said casing, a stem connected to said valve, a rod 75
30
- slidably projecting from said casing, a stock supporting said casing, disks on said stem and rod, a lever pivoted in said casing for co-action with said disks, a spring controlled member in said stock for operating said rod to cause opening of the valve, and a trigger in said stock for holding the spring controlled member in an inoperative position.
9. In a shot gun the combination with a stock, of a compressed air casing supported thereon, an air pump tube and a barrel projecting into the casing, a control valve for the barrel, a valve for the pump tube, springs for holding the barrel control valve and the pump valve closed, a pair of rods slideable in the casing with one of said rods projecting into said stock, a member pivoted in said casing co-acting with said rods, and means in the stock adapted to operate the projecting rod to cause opening of the barrel valve.
10. In an air shot gun a stock, a compressed air casing supported thereon, a barrel projecting into the casing, a valve for closing the inner end of the barrel, a stationary bracket secured in the casing, a valve stem connected with the valve and having sliding engagement with said bracket, a spring between the bracket and the valve for holding the valve closed, a rod slidably projecting through the end of the casing into the stock, a lever pivoted in the casing, disks on the valve stem and on said rod with which the lever co-acts, an operating member slideable in the stock, a trigger in the stock for holding the operating member in a release position, and means for actuating the operating member when the trigger is pulled to cause the operating member to actuate the rod, lever and valve stem to open the valve.

In testimony whereof I have hereunto subscribed my name in the presence of two subscribing witnesses.

WILLIAM PAUL.
